US00D776288S

(12) **United States Design Patent** (10) **Patent No.:** **US D776,288 S**
(45) **Date of Patent:** **** Jan. 10, 2017**

(54) **SHELL FOR AN ORTHOPEDIC DEVICE**

- (71) Applicant: **OSSUR HF**, Reykjavik (IS)
(72) Inventors: **Adam Dunn**, Laguna Niguel, CA (US);
Gil David Manalo, San Clemente, CA (US)
(73) Assignee: **OSSUR HF**, Reykjavik (IS)
(**) Term: **15 Years**
(21) Appl. No.: **29/539,730**
(22) Filed: **Sep. 17, 2015**

CLAIM

The ornamental design for a shell for an orthopedic device, as shown and described.

DESCRIPTION

FIG. 1 is a perspective view of a shell as used in an orthopedic device;

FIG. 2 is a perspective view of the shell of FIG. 1;

FIG. 3 is a left elevational view of the shell of FIG. 1;

FIG. 4 is a right elevational view of the dorsal shell of FIG. 1;

FIG. 5 is a front elevational view of the shell of FIG. 1;

FIG. 6 is a back elevational view of the shell of FIG. 1;

FIG. 7 is a top plan view of the shell of FIG. 1; and,

FIG. 8 is a bottom plan view of the shell of FIG. 1.

The broken lines are included for the purpose of illustrating environmental structure and form no part of the claimed design.

1 Claim, 6 Drawing Sheets
